UNITED STATES PATENT OFFICE.

CHRISTOPHER T. MACE, OF APPLETON, WISCONSIN.

REED FOR WEAVING LOOMS.

Application filed September 24, 1920. Serial No. 412,573.

To all whom it may concern:

Be it known that I, CHRISTOPHER T. MACE, a citizen of the United States, residing at Appleton, county of Outagamie, and State 5 of Wisconsin, have invented new and useful Improvements in Reeds for Weaving Looms, of which the following is a specification.

This invention relates to improvements in reeds for weaving looms.

10 Objects of this invention are to improve the construction of reeds for looms; to provide a reed in which the dents are individually removable without necessitating the disassembling of the entire reed; to provide a reed in which the correct spacing of 15 the dents is insured, even when a new dent replaces an old dent; to provide a reed in which the dents are not crowded toward their central portion; and to provide a reed 20 in which the clamping pressure on the dents may be varied.

Other objects of this invention are to provide a reed in which faulty threading thereof may be corrected by the insertion or removal of a dent without necessitating a re-threading of the reed; and to provide a reed 25 in which the inspection, removal, or correction of any defective dent may be quickly and readily made.

30 In the drawings:—

Figure 1 is a fragmentary elevation of a reed.

Figure 2 is a sectional view on line 2—2 of Figure 1.

35 Figure 3 is a fragmentary section on the line 3—3 of Figure 1.

Figure 4 is a view of one of the dents detached.

40 Figure 5 is a similar view of one of the spacers.

The reed comprises upper and lower reed bars indicated generally by the reference characters 1 and 2, and end members 3. Between these upper and lower reed bars a series of dents 4 are positioned in spaced relation by means of a series of spacers 5. The means for clamping the dents and spacers in position comprises the bar 6 which is inwardly pressed by means of a pair of screws 45 7 and 8 having locking nuts 9 and 10, respectively, such screws passing thru and being threaded to the end bars 3, their ends seating in sockets 11 and 12 formed in the clamping bar 6.

55 The reed bars are each composed of mem-

bers 13 and 14 formed integrally and extending at substantially right angles to each other. The member 13 is provided with a dove-tailed groove 15, and the member 14 with an inwardly projecting V-shaped rib 60 16 extending thruout their length. The reed bars further comprise retainers in the form of plates 17, which are provided with inwardly projecting V-shaped ribs 18 aligning with the ribs 16. These retaining plates 65 are secured to the member 13 by means of screws 19 countersunk in the plate 17 and threading into members 13.

The dents comprise flat, relatively wide metal plates which, when fine mesh weaving 70 is to be done are of extremely thin metal. These plates 4 are of slightly less length than the distance between the upper and lower surfaces 21 and 22 of the members 1 and 2, and are provided with notches 23, 75 corresponding to the V-shaped ribs 16 and 18 of the reed bars 1 and 2. Thus when the dents 4 are positioned within the reed bars and the retainers 17 are secured in position, the dents are carried by the V-shaped ribs 80 16 and 17 formed upon the reed bars 1 and 2. Its ends are spaced from the surfaces 21 and 22.

Figure 5 shows a spacer 5, which is formed of similar flat, relatively wide, 85 metal, and is provided with V-shaped notches 25 adapted to engage the ribs 16 and 17, and are further provided with a dovetail projection 26 which is adapted to engage within either of the dove-tailed grooves 90 15 formed in the members 13 of the reed bars.

Thus it will be seen that when the spacer strips are positioned with the projections 26 slidably held within the dove-tailed 95 grooves 15 and the dents positioned with the projections 16 and 18 engaging in the notches 23, such dents may be readily removed or replaced by removing the retainers 17, and withdrawing the dent without 100 danger of the corresponding spacer strips dropping out of position.

The end members 3 may conveniently be formed of rectangular metal pieces having projecting pins 27 formed either integrally 105 therewith or formed separately and inserted into openings within such rectangular members 3. These pins 27 are adapted to engage openings 28 formed in the members 13 of the reed bars 1 and 2. The rectangu- 110

lar members 3 are further provided with openings thru which screws 29 pass, such screws being countersunk in the members 3, and threaded into the members 14 of the reed bars 1 and 2. Thus a secure and accurate positioning of these end members 3 is secured by this method of attachment. Either one or both of the end members 3 may be provided with the adjusting clamp-
10 ing screws 7 and 8.

The clamping bar 6 is of the same width and length as the dents 4, and is correspondingly provided with notches 30 which engage the V-shaped projections 16 and 18 of the upper and lower reed bars and freely slide thereon.

It will be seen that when the clamping screws 7 and 8 are tightened, the pressure is transmitted thru the clamping bar 6 to the spacers 5, and to the dents 4. By this construction any pressure that is desired may be placed upon the dents 4, and also this pressure may be quickly removed by loosening the screws 7 and 8. When these screws are loosened it will be noted that the ends thereof may be disengaged from the sockets 11 and 12 formed in the clamping bar 6. Upon removal of the retainers 17 the bar 6 may be completely removed if desired; also the dents may be withdrawn by a direct lateral motion. If desired the spacers may be slipped out from engagement with their dove-tailed slots into the spaces 31 at the ends of the reed bars and thereafter removed.

By this construction when any of the reed dents become broken they may be readily removed and other dents may be substituted therefor without dismantling the entire 40 reed; also any fault in threading may be corrected by a proper substitution, removal or addition of dents to effect the desired spacing of the weft.

While this reed is particularly suited to 45 weaving wire, it is to be understood that the scope of this invention is not to be limited, except as defined in the following claims.

I claim:—

1. In a reed, the combination with alter-
50 nate dents and spacers, of a reed bar grooved to receive said dents and provided with a recess adapted to receive said spacers, and a retaining element associated with the bar and adapted to secure the dents thereto, said spacers being independently interlocked with the bar within said recess.

2. In a reed for a loom, the combination with an L-shaped reed bar, of a retainer adapted to be secured to said reed bar, dents 60 adapted to be held in operative position by said retainer, and spacers having means adapted to engage said bar independently of said retainer, whereby said dents may be separately withdrawn upon removal of the retainer.

3. In a reed for a loom, the combination with a reed bar having a rib, of dents having notches adapted to register with said rib, a retainer adapted to be secured to said reed bar, and spacers interposed between 70 said dents adapted for interlocking engagement with said reed bar independently of said retainer.

4. In a reed for a loom, the combination with reed bars spaced apart, having dovetailed grooves and end members connecting them at their ends, of dents carried thereby and extending between them, retainers for said dents, spacers interposed between 75 said dents having dovetailed portions adapted to engage said dovetailed grooves, and means co-operating with said end members, whereby clamping pressure may be applied to the dents and spacers.

5. A reed comprising L-shaped reed bars, 85 dents extending between said bars having their ends seated therein, spacers interposed between said dents, retainers adapted to hold said dents in operative position, and means upon said spacers adapted to engage said 90 bars independently of said retainers.

6. In a reed, the combination with alter-
nate dents with notched ends and spacers with flaring ends projecting beyond the 95 dents, of a reed bar provided with a longitudinally ribbed groove adapted to receive the dents and with a dovetailed recess with which the ends of the spacers are interlocked.

7. A reed comprising upper and lower 100 reed bars, spacing blocks at each end of said reed for spacing said reed bars apart, a bolt threaded thru one of said spacing blocks, dents extending between said reed bars and provided with notches, ribs formed 105 upon said reed bars and co-operating with said notches, spacers interposed between said dents and dove-tailed into said reed bars, and retaining members carried by said reed bars for retaining said dents and spacers, 110 whereby said bolt may apply clamping pressure to said dents and spacers, said dents and spacers freely sliding between said reed bars and retainers.

8. In a reed, a reed bar having a recessed 115 body portion, an integral longitudinally disposed flange projecting upon one side of said recess, and a removable flange spaced from the integral flange upon the other side of the recess.

9. In a reed, a reed bar having a recessed body portion, an integral longitudinal flange projecting upon one side of the recess, a removable flange upon the other side of the recess, dents receivable between said flanges, 125 and spacers alternating with said dents and independently secured with their ends projecting into said recess.

10. In a reed, a reed bar having a re-
cessed body portion, an integral longitudinal 130

flange projecting upon one side of the recess, a removable flange upon the other side of the recess, dents receivable between said flanges, spacers alternating with said dents and independently secured with their ends projecting into said recess, and means for exerting lateral binding pressure upon said dents and spacers, said dents and spacers

being slidable with respect to said bar while secured against removal therefrom.

10

In testimony whereof I affix my signature in the presence of two witnesses.

CHRISTOPHER T. MACE.
